INTERNAL-COMBUSTION ENGINE

Anthony Cadella, Fairfield, Conn.

Application January 27, 1944, Serial No. 519,863

10 Claims. (Cl. 123—78)

This invention relates to new and useful improvements in internal combustion engines and has for an object to provide an internal combustion engine having an expansible or adjustable compression chamber.

Other objects and advantages of the invention will become apparent from a consideration of the following detailed description taken in connection with the accompanying drawings where satisfactory embodiments of the invention are shown. However, it is to be understood that the invention is not limited to the details disclosed but includes all such variations and modifications as fall within the spirit of the invention and the scope of the appended claims.

In the drawings:

Fig. 1 is a central vertical sectional view through the head of an internal combustion engine having the invention incorporated therein;

Fig. 2 is a sectional view taken as along the line 2—2 of Fig. 1 and looking in the direction indicated by the arrows;

Fig. 3 is a view similar to Fig. 1 but showing a modification;

Fig. 4 is a view similar to Fig. 1 but showing another modification;

Fig. 5 is a detail sectional view of certain operating parts removed from the engine of Fig. 4;

Fig. 6 is a longitudinal sectional view on a horizontal plane through the means of Fig. 5;

Figs. 7 and 8 are detail sectional views through the operating means, the views being taken as along the lines 7—7 and 8—8, respectively, of Fig. 6.

Referring in detail to the drawings and at first more particularly to the form of the invention shown in Figs. 1 and 2, at 10 is generally indicated an engine block having a cylinder 11 therein and in which is reciprocable a piston 12 having connected thereto any or the usual piston rod 13. On the block 10 is a head generally designated 14. An opening 15 is cut through head 14 in alignment with the cylinder 11 and the sides of such opening where it passes through the inner wall 16 of the head are screw threaded as shown.

A sleeve 17 is fitted in the opening 15 and is threaded to the wall 16. Beyond head 14 the sleeve 17 is externally enlarged as at 18 whereby it includes an annular shoulder 19 overlying the outer wall 20 of the head about the opening 15. A compressible gasket 21 is located below the shoulder 19 and on the sleeve being threaded tightly home this gasket is compressed providing a seal against the escape of water or other cool-

ant from the space between the walls 16 and 20. At its inner end the sleeve 17 is provided with an internal annular lip 21a.

Within the sleeve 17 a piston device generally designated 22 is arranged in opposing relation to the outer end of the piston 12 and such piston device at its inner end is provided with an annular shoulder 22a normally seated against the lip 21a as shown. A cap 23 is threaded onto the outer end portion of the sleeve and passing centrally through said cap is a rod 24 at its outer end carrying a roller 25 engaged by a cam 26 on a shaft 27. At its inner end the rod 24 carries a plate 28 and bearing at one end against said plate and at its other end against the piston device 22 is a heavy coil spring 29. Clearly the spring 29 constantly tends to maintain the piston device 22 against the lip 21a. Openings 30 in the cap 23 prevent the entrapment of air at the outer side of the piston device.

On adjustment of cam 26 the compression of the spring 29 may be increased or decreased depending on the direction in which the cam is adjusted. Rod 27 carrying the cam 26 is preferably extended to the dash of the automobile (when the present engine is employed in an automobile) for convenience of adjustment and in a multi-cylinder engine all cylinders are constructed as herein and preferably the control cam for the piston device of each cylinder is on the same rod 27.

The piston device 22 with the piston 12 define opposing portions of the walls of a compression chamber 31 when the piston is in its outer most position as shown. A valve 32 may control the movement of fuel to such chamber. At its outer end piston 12 comprises essentially an annulus. A ring or annulus 33 is threaded into place in the outer end of the piston so that there is a central opening through the outer end of the latter. Actually piston 12 comprises inner and outer bodies 34 and 35 of which the latter has the annulus 33 threaded into its outer end portion.

Inner body 34 has a raised central outer end portion 36 of a diameter to enter and fill the opening through the annulus 33 and with the latter and the outer end of the side wall of body 35 completes the outer end of the piston 12. Surrounding raised portion 36 the body 34 has an annular shoulder 37 normally engaged with the inner side of the annulus 33 whereby outward movement of the body 34 relative to the body 35 is positively limited. A coil spring 38 bears against the inner side of the head end of the body 34 and against a bracket 39 on the wrist pin 40, see Fig. 2, and serves to constantly urge

the body 34 to a position with the mentioned annular shoulder against the inner side of the annulus 33.

In the operation of the engine the piston device 22 and the inner piston body 34 have no movement relative to the outer piston body 35 under normal conditions. The springs 29 and 38 are of such strength and are so set that the force of the normal explosion in the chamber 31 causes no movement of the piston device 22 and only movement of the inner body 34 with the outer body 35. However, on an excessive pressure being developed in the firing or compression chamber 31 the piston device 22 may move outwardly away from the lip 21a further compressing the spring 29.

This results in an enlargement of the compression and firing chamber 31 and as the piston 12 moves inwardly in the cylinder under such excessive pressure the pressure drops and the spring 29 moves the piston device 22 back toward and to its seat on the lip 21a. The construction may be planned and in fact is planned to reduce the capacity of the compression chamber so that the compression is increased as from sixty to one hundred pounds or such other figures as may be decided upon.

On firing of the compressed charge the pressure in the chamber may jump to three hundred pounds (per square inch) and immediately the piston 12 starts inwardly in the cylinder 11. As the piston so moves the pressure drops. Piston device 22 is set to be held stationary by the spring 29 on the development of the three hundred pound or other predetermined normal pressure so that the maximum efficiency of the engine is obtained. At this time inner body 34 moves as a unit with outer body 35 of the piston 12.

On excessive explosive pressure, as on pre-ignition or on increase of fuel supply and slower piston movement such as may result at the start of the climb of a hill, etc., the piston device 22 moves outwardly relieving the excessive pressure as the piston 12 starts its working stroke. As piston 12 so moves the pressure above it falls and when such pressure is back to the predetermined maximum for which the spring 29 is set the latter starts the return movement of the piston device 22 prolonging the cylinder pressure at the three hundred pounds (or other predetermined amount) maximum pressure as predetermined.

It is noted in Figs. 1 and 2 that the hole 15 has been cut through the head of an engine of standard construction as now on the market so that in such figures the invention has been applied to an existing engine. By manipulation of the shaft 27 the cam 26 may be turned in one direction or the other to further force the rod 24 inwardly or to permit the same to move outwardly whereby to increase or decrease the compression of the spring 29 and to thus change the normal maximum pressure at which the engine is to operate and yet have the piston device 22 remain stationary.

Spring 38 is of a construction to maintain the inner piston body 34 with its annular shoulder seated against the annulus 33 under the normal operating pressures developed in the engine. This spring is under somewhat less compression than the spring 29 whereby the inner piston body 34 will yield to increase the size of the compression and firing chamber on the development of an excessive pressure while the piston device 22 will yield only on development of a pressure in excess of that required to unseat the device 34.

Thus the constructions may be used to supplement one another. However, it is to be understood that either structure may be used alone. When the inner piston body 34 is used and the piston device 22 is not used the entire task of enlarging the compression chamber and relieving excessive pressure therein and of prolonging the application of full maximum pressure to the piston 12 is performed by the said inner piston body 34 in movements relative to movements of the outer piston body 35.

In Fig. 3 the invention is shown as incorporated in a new construction wherein the engine block and head are formed as an integral casing 15 including a lower or block portion 45 having a cylinder 46 therein and an outer or head portion 47 having a bore 48 therethrough in the nature of an extension of the cylinder 46. Within the cylinder 46 and reciprocable toward and from the outer end thereof is a piston 49 connected with a piston rod 50.

A piston device is disposed in the bore 48 in opposing relation to the piston 49 and with the latter defines a small capacity compression and 25 firing chamber. At its outer end the piston device 51 includes a radial flange portion 52 overlying the end of the portion 47 whereby movement of the device into the passage in the direction of the piston 49 is positively limited. A cap 53 is 30 threaded over the outer end of the portion 47 and threaded through the cap is the shank of a screw 54 at its inner end bearing against a plate 55. Between the plate 55 and the head of the piston device 51 is a coil spring 56 normally serving 35 to retain the device in position with its flange 52 against the outer end of the body portion 47. On loosening of a lock or jam nut 57 about the shank of the screw the latter may be adjusted to increase or decrease the compression of the 40 coil spring 56 whereby to change the predetermined pressure at which the piston device will be moved away from the piston 49 or outwardly in the passage 48.

The device of Fig. 3 functions in the same manner as the device 22 of Figs. 1 and 2. In the structure of Fig. 3 the engine block is specially formed and it is not necessary to cut an opening through an engine head as in Figs. 1 and 2 wherein the invention is disclosed as added to or incorporated in an existing engine. Further in the device of Fig. 3 it is necessary to make individual or separate and independent adjustments of the screws 54 of the various cylinders of the engine whereas in Figs. 1 and 2 the adjustments are simultaneously made for all the cylinders of the same engine bank by manipulation of the rod or shaft 27 carrying the cams 26 over the rods 24 of the various cylinders of such bank.

Referring now to Figs. 4 through 8 the invention is shown as incorporated in an engine including a block 60 and a head 61. Block 60 has a cylinder 62 therein and in which is reciprocable a piston 63 secured to a piston rod 64. A cylindrical bore 65 is formed through the head 61 and is defined by a cylindrical wall 66 projecting beyond the upper side of the engine head. A cap 67 is threaded to the upper projecting portion of the wall 66 and may be provided or formed with a sort of funnel device 68 for directing air through an opening 69 in the cap. The cap is provided with other openings for the free movement of air therethrough and the directing of air through the cap is for the purpose of helping to cool the piston device 70 now to be considered. 75 Piston device 70 is arranged in the bore 65

with its head end in opposing relation to the piston 63 and rigidly connected with said piston device and extending outwardly through the cap 67 is a rod or stem 71 having at its outer end a head 72 provided in its side walls with slots 73 extending at or substantially at right angles to said rod or stem. A bracket 74 has a bifurcated upper end receiving between its arms 75 a bar 76 arranged substantially horizontally. Between the arms 75 the bar 76 is provided with a circular opening in which is fitted a cam disc 77 through which eccentrically passes a shaft 78 rotatably supported in the bracket arms 75.

10 A bracket or support 79 under the outer end of the bar 76 mounts a coil spring 80 bearing at its upper end against a plate 81. A screw 82 is threaded through the outer end of bar 76 into engagement with the plate 81 and thus the spring 80 is constantly tending to move the outer end portion of bar 76 outwardly in a direction away from the engine. Also mounted on cap 67 is a bracket means 83 to which is pivoted a link-like means 84 the outer end portion of which is bifurcated and straddles the bar 76 at a point between the screw 82 and the shaft 78.

15 A stop in the form of a pin or roller 85 is mounted between the outer ends of the arms of the means 84 and inwardly of such roller a pin 86 passes through the bar 76 and has its ends disposed in slots 87 in the arms of the said means. Mounted on this pin 86 between the arms of the means 84 and at one side of the bar 76 is a dog or rocker 88 adapted for pivotal movement and having an extension 89 to which is connected a coil spring 90 constantly tending to rock the dog about its pivot whereby to maintain it in contact with the roller 85. A cross pin 91 carried by the inner end portion of the bar 76 and extending into the slots 73 provides a pin and slot connection between said bar and the head 72.

20 In the operation of the engine of Fig. 4 the piston device 70 functions much the same as the piston devices of the figures previously described. The disc or cam 77 is preset to dispose the piston device in the desired relation to the piston 63 when the device is in its normal or innermost position. Similarly the screw 82 is adjusted to have the spring 80 functioning through the bar 76, as a lever pivoted on disc 77, exert the desired and predetermined pressure to maintain the piston device in such preset position against normal explosive pressures in chamber 92.

25 However, on creation of an excessive pressure in chamber 92 the piston device 70 is forced outwardly rocking the arm 76 about the disc 77 as a pivot and compressing the spring further. As the excessive pressure is relieved on the working stroke of the piston 63 the spring 80 acting through the bar or arm 76 forces the piston device 70 back to normal position, the movement of the bar 76 about the disc 77 being limited by the roller or pin 85.

30 On any rocking movement of the bar 76 caused by outward movement of the piston device 70 the pivoted dog 88 (as it is carried with the bar) is rocked on its pivot by the coil spring 90 and kept in mechanical engagement with the pin 85. Thus the dog is always in engagement with the pin 85 and on reverse movement of the bar 76 by the spring 80 as the bar moves upwardly the dog is rocked back about its pivot but staying in contact with the pin 85 at all times there is no noise or clicking at the end of the upward movement of the outer end portion of bar 76. In other words the take up device described pro-

vides for zero clearance between the parts at all times.

35 In this third modification the firing and compression chamber is made of small capacity as in the other forms of the invention disclosed. On development of an excessive pressure the device 70 moves upwardly relieving the pressure somewhat by enlarging the cubic capacity of the firing and compression chamber and then moves downwardly in the direction of movement of the piston prolonging the application of the maximum pressure to the latter. The maximum downward movement of the piston device is determined by the movement of the bar 76 about the disc 77 and such movement is limited by the roller or pin 85 and the means 84.

40 Disc or cam 77 also provided a means for making an adjustment of the device 70 toward the piston 63 whereby to reduce the cubic capacity of the compression chamber 92 to compensate for wear of the piston 63 and the consequent loss of compression. For example, if the original and desired compression pressure is one hundred pounds and because of leakage caused by wear 45 of the piston 63 the compression pressure being obtained is only ninety pounds the disc or cam 77 is adjusted to lower the pivot point of the bar 76 and thus lower the piston device 70 in the cylinder 65 reducing the cubic capacity of the chamber 92 so that the compression obtained therein will be increased. This adjustment of the cam 77 results in a rocking of the bar 76 to carry its outer end away from spring 80 and now screw 82 is adjusted through the bar to restore the 50 spring to the desired compression.

45 While the take up device between the relatively movable parts 76 and 85 is herein disclosed as applied to the control of the piston device 70 it is to be understood that such take up device is 55 of general application for the purpose of maintaining zero clearance between a pair of parts. This structure may be used in engine valve tappet structures to prevent tappet noises, etc. It includes means for maintaining mechanical contact and thus zero clearance between a pair of relatively movable parts, the contact being, in the present instance maintained by the spring urged dog 88 and the pin or roller 85.

50 The structures including the piston devices of the various figures provide for engines of higher than usual operating pressures and for the avoiding of engine knock. While the present structures provide for extra high compression, since they allow for only a small capacity of compression chamber while providing for the customary size of charge, they also provide expandible or adjustable compression chambers whereby engine knock is avoided. Thus with the present structures an engine to use higher octane gasoline is provided and one taking full advantage of the 55 possibilities of such fuel for efficient operation.

55 While the cam 26 has been described as manually adjustable by rotation or turning of the shaft 27 it is contemplated that this shaft be controlled according to the speed of the engine as by a vacuum operated means or the like. Thus as a car equipped with the engine starts to climb a hill the cam may be adjusted to somewhat relieve the compression of the spring 29 so the 60 piston device 22 may be unseated with a less pressure.

65 Somewhat similarly the cam or disc 77 may be either manually or automatically adjusted. In this connection it is to be understood that in a 70 multi-cylinder engine the cams 77 of the various

cylinders will all be mounted on the same shaft 18. As a car equipped with such an engine starts slowly up a grade the cams 17 are either manually or from the engine adjusted to slightly raise the piston device 10 to enlarge the compression chamber whereby there will be a drop in compression pressure and knocking in the engine will be avoided. At the proper time the cams or discs 17 are returned to their normal positions.

Having thus set forth the nature of my invention, what I claim is:

1. In an internal combustion engine, an engine block having a cylinder therein, a head on said block, a piston in said cylinder and reciprocable toward and from said head, said head having an opening therethrough in alignment with said cylinder, a sleeve extending through said head and providing side walls for said opening, an internal lip at the inner end of said sleeve, a piston device in said sleeve in opposing relation to the piston and cooperating with the latter when it is at the outer end of its stroke to define a compression chamber, a cap closing the outer end of said sleeve, a rod movable through said cap, a plate on the inner end of said rod, a coil spring bearing at its respective ends against said plate and the piston device and constantly tending to keep the latter against said lip, and adjustable cam means adjustable to cause movement of said rod to decrease and increase the compression of said spring depending on the direction of movement of the cam.

2. In an internal combustion engine, an engine block having a cylinder therein, a head on said block, a piston in said cylinder and reciprocable therein toward and from said head, said head having an opening therethrough in alignment with said cylinder, a sleeve threaded into and extending through said head and providing side walls for said opening, a piston device in said sleeve in opposing relation to the piston and cooperating with the latter when it is at the outer end of its stroke to define a compression chamber, a cap closing the outer end of said sleeve, a rod movable through said cap, a plate at the inner end of said rod, a coil spring bearing at its respective ends against said plate and the piston device and constantly tending to move the same inwardly in said sleeve, a stop limiting inward movement of the piston device by said spring, and cam means adjustable to cause movement of said rod to decrease and increase the compression of said spring depending on the direction of movement of the cam.

3. In an internal combustion engine, an engine block having a cylinder therein, a piston reciprocable in said cylinder toward and from the outer end thereof, a head on said block and having a cylindrical passage therethrough providing in effect a continuation of said cylinder, a piston device in said passage in opposed relation to the outer end of said piston and with the latter defining a compression chamber at the outer end of the cylinder when the piston is in its outermost position, a cap closing the outer end of said passage, a rod connected with said piston device and slidable through said cap, an arm having at one end a head connected with the outer end of said rod by a pin and slot connection, a screw passing through the other end portion of said arm and at the inner side thereof connected with a plate, a coil spring bearing against said plate and normally tending to act therethrough and move said other end portion of the

arm outwardly away from the engine, said arm having a circular opening therein intermediate its ends, a disc in said opening, a bracket mounting a shaft passing through said disc in eccentric relation thereto whereby on rotation of the shaft the disc acts as a cam to raise and lower the arm and thus raise and lower the piston device in said passage against the action of said spring.

4. In an internal combustion engine, an engine block having a cylinder therein, a piston reciprocable in said cylinder toward and from the outer end thereof, a head on said block and having a cylindrical passage therethrough providing in effect a continuation of said cylinder, a piston device in said passage in opposed relation to the outer end of said piston and with the latter defining a compression chamber, a cap closing the outer end of said passage, a rod connected with said piston device and slidable through said cap, an arm having at one end a head connected with the outer end of said rod by a pin and slot connection, a screw passing through the outer end portion of said arm and at the inner side thereof connected with a plate, a coil spring bearing against said plate and normally tending to act therethrough and move said other end portion of the arm outwardly away from the engine, said arm having a circular opening therein intermediate its ends, a disc in said opening, a bracket mounting a shaft passing through said disc in eccentric relation thereto whereby on rotation of the shaft the disc acts as a cam to raise and lower the arm and thus raise and lower the piston device in said passage against the action of said spring.

5. In a take up device, a pair of parts of which one is movable toward and from the other, cam means providing mechanical contact between said parts, and spring means causing said cam means to move and maintain said mechanical contact between said parts on movement of one of said parts in a direction from the other thereof.

6. In a take up device, an arm, a bracket having a passage receiving said arm, a roller at the outer end of said passage and toward and from which said arm is movable, said bracket having slots in its portions at the sides of said passage and extending in the direction of said roller, a pin passing through said arm and movable in said slots for guided movement of the arm toward and from said roller, a cam pivoted on said pin at one side of said arm, and a coil spring constantly tending to rock said cam on said pin and serving to thereby maintain the cam in mechanical contact with the roller at all times as the pin and arm move toward and from the roller within the limits of said slots.

7. In an internal combustion engine, an engine block having a cylinder therein, a piston reciprocable in said cylinder toward and from the outer end thereof, a head on said block and having a cylindrical passage therethrough providing in effect a continuation of said cylinder, a piston device in said passage in opposed relation to the outer end of said piston and with the latter defining a compression chamber at the outer end of the cylinder when the piston is in its outermost position, a cap closing the outer end of said passage, a rod connected with said piston device and slidable through said cap whereby the piston

device is movable toward and from the piston, and a cam means adjustable to control such movement.

8. In an internal combustion engine, an engine block having a cylinder therein, a piston reciprocable in said cylinder toward and from the outer end thereof, a head on said block and having a cylindrical passage therethrough providing in effect a continuation of said cylinder, a piston device in said passage in opposed relation to the outer end of said piston and with the latter defining a compression chamber at the outer end of the cylinder when the piston is in its outermost position, a cap closing the outer end of said passage, a rod connected with said piston device and slideable through said cap, an arm having at one end a head connected with the outer end of said rod by a pin and slot connection, said arm having a circular opening therein intermediate its ends, a disc in said opening, a bracket mounting a shaft passing through said disc in eccentric relation thereto whereby on rotation of the shaft the disc acts as a cam to raise and lower the arm and thus raise and lower the piston device in said passage.

9. In an internal combustion engine, an engine block having a cylinder therein, a piston reciprocable in said cylinder toward and from the outer end thereof, a head on said block and having a cylindrical passage therethrough providing in effect a continuation of said cylinder, a piston device in said passage in opposed relation to the outer end of said piston and with the

- latter defining a compression chamber, a cap closing the outer end of said passage, a rod connected with said piston device and slideable through said cap, an arm having at one end a head connected with the outer end of said rod by a pin and slot connection, said arm having a circular opening therein intermediate its ends, a disc in said opening, a bracket mounting a shaft passing through said disc in eccentric relation thereto whereby on rotation of the shaft the disc acts as a cam to raise and lower the arm and thus raise and lower the piston device in said passage, a stop device limiting rocking movement of said arm about said disc, a rocker on said arm, and a spring constantly tending to shift said rocker and thereby maintain it in mechanical contact with said stop in all positions of the arm.
10. In an internal combustion engine, an engine block having a cylinder therein, a piston reciprocable in said cylinder toward and from the outer end thereof, a head on said block and having a cylindrical passage therethrough providing in effect a continuation of said cylinder, a piston device in said passage in opposed relation to the outer end of said piston and with the latter defining a compression chamber at the outer end of the cylinder when the piston is in its outermost position, a rod connected with said piston device, and a cam means adjustable to operate on said rod and vary the position of said piston device in relation to said piston.

ANTHONY CADELLA.
